DRAFT RIGGING

Donald S. Barrows, Rochester, N. Y., assignor
to The Symington Company, New York, N. Y.,
a Corporation of Maryland

Application July 25, 1927. Serial No. 208,284

8 Claims. (Cl. 213—60)

This invention relates to draft rigging and, more particularly, to a combined striking casting and sill tie member with a removable coupler carrier.

5 The principal object of my invention, generally considered, is the provision of a combined striking casting and sill tie member, with a removable carrier for an associated swivel butt coupler, said carrier being of simple and inexpensive construction and the combined casting being adapted for readily receiving said carrier and securely holding the same in place.

Another object of my invention is the provision of a combined striking casting and sill tie member 15 so constructed that sufficient opening is provided for the insertion and removal of the complete swivel butt of an associated coupler, a removable carrier being provided for supporting said coupler when in place.

20 A further object of my invention is to provide a removable carrier for use with a combined striking casting and sill tie member, said carrier preferably comprising a piece of standard angle iron which may be positioned even when an associated coupler is in place by inserting a flange thereof between the stem of said coupler and supporting shelves on the casting, and means preferably involving a transverse bolt passed through the striking casting back of the vertical 25 flange of said angle iron for locking the same in position against adjacent webs on said casting.

Other objects and advantages of the invention relating to the particular arrangement and construction of the various parts will become apparent as the description proceeds.

35 Referring to the drawing illustrating my invention, the scope whereof is defined by the appended claims:

Figure 1 is a plan of draft rigging showing my 40 improved form of swivel butt coupler, the associated combined striking casting and sill tie member as well as the connected sills being illustrated in section on the line 1—1 of Figure 3 looking in the direction of the arrows.

45 Figure 2 is a longitudinal vertical sectional view on the line 2—2 of Figure 1 looking in the direction of the arrows.

Figure 3 is a front elevation of my combined casting, a portion thereof illustrated in section 50 on the line 3—3 of Figure 1 looking in the direction of the arrows.

55 Referring to the drawing in detail, like parts being designated by like reference characters, there is illustrated a combined casting 1 formed with a coupler striking or stop portion 2 and a

sill tie portion or member 3 connected by substantially upright side portions 4 formed with rearwardly extending connecting ears or flange portions 5 which, in the embodiment shown, are fastened to associated sills 6 by means of a plurality of rivets 7. The sills are shown slotted as indicated at 8 and the rearwardly extending flange portions or webs 5 are correspondingly slotted as indicated at 9 and form the forward portions of cheek plates, the rear portions of 65 which are not shown, and are adapted to reinforce the slotted portions of the sills which are adapted to receive a usual form of draft key 10, as will be understood.

The striking casting portion 2 of the combined 70 casting is preferably formed with an upright web portion 11 adapted to engage with the horn of the coupler 12 upon sufficient rearward movement thereof and a lower inwardly extending flange or web portion 13 overlying the shank or 75 stem of said coupler. Extending from the upper edge of the web portion 11 and continued rearwardly is a shelf or web portion 14. The rearward portion of said shelf 14 may be downwardly offset as indicated at 15 to extend beneath and be 80 connected with an associated sill cover plate (not shown). The upper flange is and adjacent portion of the web 17 of the sills 6 are preferably cut away as indicated at 18 to receive the shelf portion 15 of the casting. For bracing the web portions 11, 13, 14 and 15 together, longitudinally extending web portions 19 are preferably provided which gradually taper from the rear edge of the web 13 and finally merge into the web 15.

85 The sill tie portion 3 of the combined casting is 90 preferably formed with a web 20 and depending flanges 21 at opposite edges thereof. The end portions of said web preferably merge into the corresponding lower ends of the webs 22 of the side portions 4 of the casting and the end portions of the front and rear flanges 21, respectively, merge with the front flanges or webs 23 and the rear flanges or webs 24 of said casting. It 95 will be apparent that the front flanges 23 of the casting extend inwardly from the web 22 thereby narrowing the front opening through the casting whereas the rear flanges 24 are offset outwardly with respect to the front flanges thereby providing a larger opening from the rear of said combined casting 1.

100 For supporting the associated coupler 12 at the proper elevation, a removable carrier or carry iron 25 is provided, said carrier preferably being in the form of a standard angle iron with a forward vertical and depending flange 26 and an 110

upper horizontal flange 27, said upper flange 27 underlying and adapted to directly support the stem of the coupler 12. The combined casting 1, in order to properly support the removable carrier 25, is provided with shelf portions 28 and 29 extending inwardly from the webs 22. The shelves 28 preferably comprise a horizontal portion 30 directly underlying and supporting the horizontal flange 27 of the carrier 25 and a substantially triangular bracing flange or web 31 depending therebeneath. The shelf portions 29 are disposed lower than the shelf portions 28 for supporting the flange 27 by directly engaging the lower edge thereof. Inasmuch as said shelf portions 29 are only a slight distance above the sill tie member 3, and are positioned lower than the shelf portions 28, they may be formed as simple stools or blocks extending upwardly from the web 20 and inwardly from the webs or flanges 23. In order to limit vertical movement of the carrier 25, stop portions 32 are provided extending inwardly from the webs 22, as illustrated particularly in Figures 2 and 3, with just enough clearance with respect to the flange 27 for permitting insertion of the carrier as will be described hereinafter.

In order to lock the carrier 25 as illustrated, a locking member preferably comprising a bolt 33 is provided, said bolt extending through aligned apertures 34 in the webs 22 of the side members 4 and, in the embodiment illustrated, being provided with a head 35 at one end and threaded for the reception of a nut 36 at the other end. A washer 37 may be used, if desired, and a cotter 38 is desirably provided for preventing the nut 36 from working off the end of the bolt when in use. The apertures 34 are so positioned that the vertical flange or leg 26 of the carrier 25 is closely engaged between the bolt 33 and the webs or flanges 23 on the casting.

The stem portion 39 of the coupler 12 is preferably pivotally connected to the swivel block or butt portion 48 to form a swivel butt coupler, as by means of pivot pins 44 and 45.

Because of the relatively large opening provided through the combined casting 1, when the carrier 25 is removed, the swivel block may be assembled with the coupler stem before insertion to position. When in position as illustrated, it is adapted to associate with cushioning mechanism and associated parts of draft rigging in any well known manner.

The carrier 25 may be inserted in position in the following manner. Inasmuch as the opening through the combined casting 1 is restricted by the flanges or webs 23, the carrier 25 is inserted from the back of the casting after the swivel butt of the coupler is in place as indicated in Figure 2, said coupler, however, being raised slightly so as to permit the flange 27 of the carrier to be swung therebeneath by being rotated slightly clockwise to the position illustrated. After positioning said carrier 25 so that the flanges 26 and 27 are, respectively, supported on the shelves 29 and 28, the flange 26 being positioned close to the flanges 23, the bolt 33 is inserted in position immediately back of the vertical leg 26 of the angle iron carrier thereby locking the same securely in position as it will be obvious that the clearance provided between the horizontal leg 27 and the flanges 32 is not sufficient to permit removal of said carrier while the bolt 33 is in place. Said bolt may then be locked in position in any desired manner as by means of the nut and cotter heretofore described.

From the foregoing, it will be seen that I have

devised an improved draft rigging involving a combined casting in which the opening there-through is of sufficient size to receive a coupler butt of abnormal size so that the swivel butt of a coupler may be inserted after assembly. Likewise, it will be apparent that, on account of the removable carrier which may be positioned without difficulty after the coupler is in place, I have provided for conveniently supporting the coupler at the desired elevation.

Having now described my invention, I claim:

1. In a railway draft rigging, in combination with a coupler having an enlarged butt, a combined casting comprising portions serving, respectively, as a striking casting and sill tie member, said tie member being spaced sufficiently from the striking portion to permit the free insertion and removal of the butt of the coupler, said casting being formed with inwardly extending shelf portions disposed at a plurality of elevations intermediate the striking casting and sill tie member, and a removable carrier comprising horizontal and vertical portions and supported at its ends, with the horizontal portion resting on the high shelf portions and the vertical portions resting on the low shelf portions, and adapted to extend beneath the stem of the coupler for the support thereof.

2. In a railway draft rigging, in combination with a coupler having an enlarged butt, a combined casting comprising portions serving, respectively, as a striking casting and sill tie member, said tie member being spaced sufficiently from the striking portion to permit the free insertion and removal of the butt of the coupler, said casting being provided with inwardly extending shelf portions intermediate the striking casting and sill tie member, and an angle iron serving as a removable carrier, disposed with a forward vertical flange and an upper horizontal flange immediately underlying the stem of the coupler for supporting the same, the ends of said vertical flange being supported on some of said shelf portions and the ends of said horizontal flange on other of said shelf portions.

3. In a railway draft rigging, in combination with a coupler having an enlarged butt, a combined casting comprising portions serving, respectively, as a striking casting and sill tie member, said tie member being spaced sufficiently below the striking portion to permit the insertion and removal of the butt of the coupler, said casting being formed with inwardly extending shelf portions disposed at a plurality of elevations and a piece of standard angle iron inserted from the back of the combined casting with a horizontal flange supported on the shelf portions at the higher elevation, and an upright depending flange supported on the shelf portions of lower elevation, said angle iron serving as a removable carrier for the support of the coupler.

4. A combined casting comprising portions serving, respectively, as a striking casting and sill tie member, said tie member being spaced a greater distance than normal from the striking casting for receiving a coupler such as a swivel butt coupler with an unusually large butt portion, said casting being provided with shelf portions extending inwardly from the sides thereof and disposed at relatively high and low elevations intermediate the striking casting and sill tie member, and a section of angle iron entered from the back of the casting and partially rotated about its own axis until one leg thereof is substantially horizontal and supported on the

relatively high shelf portions and the other leg is disposed substantially vertical with its lower edge supported on the relatively low shelf portions, said angle iron, when so positioned, being adapted to support the stem of an associated 5 coupler as a carrier therefor.

5. A combined casting comprising portions serving, respectively, as a striking casting and sill tie member, said tie member being spaced 10 sufficiently from the striking portion to provide for the free insertion and removal of the complete swivel butt of an associated coupler, means extending inwardly from the sides of said casting for supporting, respectively, a horizontal flange 15 and vertical flange of a removable angle iron, said casting being formed with a transverse web portion extending inwardly from the front face of the casting and preventing insertion of the angle iron from the front, said casting being formed 20 to permit insertion of said angle iron from the rear upon rotation thereof about its longitudinal axis until it is supported on the shelf portions, and means for locking said angle iron when in place comprising a removable member extending 25 between the sides of the casting behind the vertical flange of the angle iron for holding said flange against the transverse web portion of the casting and preventing rotation and removal thereof.

30. 6. A combined casting comprising portions serving, respectively, as a striking casting and sill tie member, said tie member being spaced sufficiently from the striking portion to permit the free insertion and removal of the enlarged 35 butt of a coupler, said casting being formed with integrally extending shelf portions spaced from both the striking casting and sill tie portions of the casting, and a removable carrier with an upper flange supported on said shelf portions

and adapted to extend beneath the stem of the associated coupler for the support thereof, and a side flange, said sill tie member having stool portions underlying the ends of said flange for supporting the same.

7. A combined casting comprising portions serving, respectively, as a striking casting and sill tie member, said tie member being spaced sufficiently from the striking casting to permit the free insertion and removal of the stem of a coupler with an enlarged butt, said casting being provided with inwardly extending shelf portions intermediate the striking casting and sill tie member, and an angle iron serving as a removable carrier supported at the ends of one flange thereof on said shelf portions and disposed with the other flange substantially vertical and resting at its ends on projections from the sill tie member and adapted to underlie and support an associated coupler.

8. A combined casting comprising portions serving, respectively, as a striking casting and sill tie member, said tie member being spaced sufficiently from the striking casting to permit the insertion and removal of the enlarged butt 100 of an associated coupler, the sides of said casting connecting said striking casting and sill tie portions being formed with inwardly extending supporting portions disposed at relatively high and relatively low elevations, and a section of 105 angle iron inserted with one flange horizontal and the other vertical and the horizontal flange supported on the shelf portions at the relatively high elevation and the other flange supported on the shelf portions at the lower elevation whereby 110 said angle iron is adapted to serve as a removable carrier for the support of an associated coupler.
